(57) **CLAIM**

The ornamental design for a dental accessory for holding a saliva ejection tube, as shown and described.

DESCRIPTION

FIG. 1 is a front perspective view of a dental accessory for holding a saliva ejection tube according to a first embodiment of my design;

FIG. 2 is a front elevational view thereof;

FIG. 3 is a rear elevational view thereof;

FIG. 4 is a first side elevational view thereof;

FIG. 5 is a second side elevational view thereof;

FIG. 6 is a top elevational view thereof;

FIG. 7 is a bottom elevational view thereof;

FIG. 8 is a front perspective view of a dental accessory for holding a saliva ejection tube according to a second embodiment of my design;

FIG. 9 is a front elevational view thereof;

FIG. 10 is a rear elevational view thereof;

FIG. 11 is a first side elevational view thereof;

FIG. 12 is a second side elevational view thereof;

FIG. 13 is a top elevational view thereof; and,

FIG. 14 is a bottom elevational view thereof.

The broken line showing of various features is for the purpose of illustrating unclaimed portions of the dental accessory for holding a saliva ejection tube and forms no part of the claimed design.
